Primary Examiner—Stella Reid**Attorney, Agent, or Firm**—Anna Ganelina; Thomas A. Powers; Chandrakant C. Shroff**[57] CLAIM**

The ornamental design for a vibrating body massaging device, as shown.

DESCRIPTION

FIG. 1 is a top, front and side perspective view of a vibrating body massaging device showing my new design;

FIG. 2 is a top plan view thereof; and,

FIG. 3 is a side view thereof, the opposite side view being identical thereto.

The bottom of the article is plain and unornamented.
